(57) **CLAIM**

I claim the ornamental design for a swimming pool cleaner robot, as shown and described.

DESCRIPTION

FIG. 1 is a front view of the new design for a swimming pool cleaner robot;

FIG. 2 is a back view of the new design for a swimming pool cleaner robot;

FIG. 3 is a top view of the new design for a swimming pool cleaner robot;

FIG. 4 is a bottom view of the new design for a swimming pool cleaner robot;

FIG. 5 is a right side view of the new design for a swimming pool cleaner robot;

FIG. 6 is a left side view of the new design for a swimming pool cleaner robot;

FIG. 7 is a perspective view of the new design for a swimming pool cleaner robot; and,

FIG. 8 is a perspective view thereof, showing the handle in an alternate position.
